FOUR-IN-HAND NECKTIE

Alfred Scharlin, Brooklyn, N. Y.

Application November 2, 1936, Serial No. 108,790

6 Claims. (Cl. 2—150)

This invention relates to four-in-hand neckties and to methods of making the same.

One object of the invention is the provision of a necktie of the character described having an improved arrangement and construction so as to adapt the same for commercial sale and use without the necessity of tying a knot. Generally stated, the invention provides an improved feature wherein neckties are provided for sale with preformed knots and in condition for immediate wear.

Another object of the invention is the provision of a necktie of the nature set forth having a preformed knot and improved means co-operating therewith such that the knot will not ordinarily open nor loose its initial configuration, and the knot being applied to and removed from the wearer by utilizing the slip action afforded by the knot.

Another object of the invention is to provide an improved necktie having relatively few and simple parts, and which is inexpensive to manufacture and assemble, neat in appearance and durable and reliable to a high degree in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in front elevation showing a necktie embodying the invention.

Fig. 2 is a view in rear elevation thereof.

Fig. 3 is a sectional view taken on the line 3—3 of Fig. 1.

Fig. 4 is a sectional view taken on the line 4—4 of Fig. 1.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes

a device embodying the invention. The same includes a four-in-hand tie of a conventional type, but having a novel feature that the knot 11 is preformed in the course of manufacture of the necktie, so that the purchaser receives a necktie already made up as shown in Fig. 1. Consequently in order to apply the necktie 10 to his person, the wearer need merely slip the neck portion 12 of the necktie around his collar, and then pull downward on the rear portion 13 in order to draw the neck portion tight, whereupon the necktie is fully operatively mounted and with the front portion 14 thereof in its proper predetermined and accurately folded relation to the knot 11.

So far as I am aware, it has never been known to produce and market a necktie according to the arrangement disclosed in Fig. 1, and whereby a particularly neat and attractive appearance is produced, since the purchaser can directly perceive the appearance of the necktie, and especially because the arrangement at the knotted portion of the necktie is accurately preformed by people who are expert in that respect. It is well known that many persons are unable to accurately and neatly tie the knot of a necktie for the purpose of obtaining the desired decorative effect. Various attempts have been made to solve this difficulty, as by the use of split collar bands, but these have their own peculiar defects which are avoided by the present invention.

In order to assure correct maintenance of the arrangement and configuration of the necktie, and to permit the same to be constantly applied, and removed from the wearer without opening the knot, I have, by way of carrying forward this inventive concept, provided a stop element 15 on the rear necktie portion 13. This stop element may be in the nature of a lateral projection such as a button, ornament, or the like, stitched or otherwise secured or formed on or as a part of the rear necktie portion 13, so that the portion 15 will act as an obstruction at or adjacent to the knot 11 to prevent the rear tie end 13 from being pulled out through the knot 11. In this manner when a person is enlarging the necktie band portion 12 for removing the necktie, he can not, as a result of a rapid movement, accidentally pull out the rear tie end 13 and thus disassemble the knot 11.

In ordinary course of use of a necktie, the same is subject to various pulls and other stresses which tend to bring about a deformation of the knot and which have a tendency to throw the front tie end 14 out of correct relation thereto, so

that unless the knot is often opened up and retied, the necktie eventually assumes an ill formed appearance. To carry forward the inventive concept hereinbefore mentioned, I provide one or more auxiliary features, one of which may consist in a tacking at 16 wherein certain plies of the knot 11 are interconnected at the rear thereof so as to prevent accidental opening or loosening of the knot, and also to prevent relative vertical shifting of the parts thereof. Another feature may consist in the provision of a transverse loop portion 17 connected to the front tie end 14 as at the edges 18 thereof and disposed wholly at the rear of the necktie and at or in relative proximity to the knot 11. This loop portion may extend around the rear tie end 13 so as to tend to center the same. Other features of advantage in connection with the elements 16 and 17 will now be described.

20 It will be noted that the element 16 by being located substantially adjacent to the lower end of the knot, does not prevent the knot 11 from being enlarged or contracted in the well known manner. For example, if the particular wearer 25 desires a small and rather tight knot 11, he may pull downward at the front tie end 14, thereby causing the material at 19 to be pulled downward into the knot with resilient tightening of the knot. Such an action will not be prevented 30 by the tacking at 16, and, moreover, the latter will permit the knot to maintain a decorative configuration.

I have observed that the front tie end 14 always tends to shift at the knot 11 toward the right or the left, depending upon the manner in which the knot 11 is formed. For example, referring to Fig. 3, it is seen that the front tie end 14 is pushed laterally within the knot by the rear tie end 13 and the loop 20 which encircles the 40 latter and extends upward to the neck. In a newly tied necktie, the front tie end 14 may be accurately centrally positioned as shown in Fig. 1, but eventually it tends to slip over toward a side, thus detracting from the appearance of the 45 necktie. This action is particularly pronounced at the edge 21 of the tie end 14 whereas the opposite edge 22 generally maintains its predetermined position since there is no room for it to slip around nor is there anything to push it from 50 its position. Hence the loop element 17 by interconnecting the edges 21, 22 as shown at 18, serves to anchor the edge 21 to maintain the front tie end 14 centralized. Nevertheless the 55 provision of the loop element 17 does not prevent the front tie end 14 from being pulled downward to tighten the knot to form a smaller knot as hereinbefore described.

It will be noted that the element 17 may consist of a rigid or flexible element and may be 60 in the nature of a thread. This element may have the additional function of serving as a guide for the rear tie end so as to prevent the latter from twisting or turning because of movement through the knot. It will be observed that the 65 obstruction at the lower portion of the rear tie end may be formed on opposite faces thereof to assure engagement with an edge of the knot so that no portion of the obstruction may enter and become caught within the knot. Since the rear 70 tacking is at the lower edge of the knot, it is well adapted to immediately resist any pull that may be caused by the said obstruction.

It is thus seen that I have provided a necktie which fulfills all the objects of the invention and 75 is well adapted for practical use.

I claim:

1. A four-in-hand necktie having a neckband portion, front and rear tie end portions integral therewith, a slip knot formed from said portions and maintaining said portions in relation to each other, said knot including a plurality of plies or turns transverse of the front and rear tie end portions, the front tie end extending downward through the knot, and means for interconnecting certain of said turns adjacent to the lower end of the knot to prevent opening of the knot and to permit the knot to be tightened by pulling downward on the front tie end, the said plies being otherwise free of each other to facilitate shaping of the knot. 15

2. A four-in-hand necktie having a neckband portion, front and rear tie end portions, a slip knot maintaining said portions in relation to each other, tacking for interconnecting portions of the knot solely at the lower end thereof to 20 prevent opening thereof, and means on the rear tie end in relative proximity to the lower end thereof to constitute an obstruction to prevent the rear tie end from being pulled through the knot to accidentally open the same, the first 25 named means adapting the knot to withstand the said obstruction, and the knot being adapted to be hand-shaped above the tacking.

3. A four-in-hand necktie having a neckband portion, front and rear tie end portions, a slip 30 knot maintaining said portions in relation to each other, said knot including a plurality of plies or turns transverse of the front and rear tie end portions, the front tie end extending downward through the knot, and means for interconnecting certain of said turns solely adjacent to the lower end of the knot to prevent opening of the knot and to permit the knot to be shaped and tightened above said means by pulling 35 downward on the front tie end, the rear tie end being freely movable through the knot to expand and contract the neckband portion, and an obstruction on an end of the rear tie end to abut the lower portion of the knot and prevent the rear tie end from being wholly pulled 40 through the knot and the obstruction from entering the knot. 45

4. A four-in-hand necktie including front and rear tie ends, a neckband portion, and a knot, the front tie end extending downwardly through the 50 knot and whereby the latter can be tightened by pulling downward on the front tie end, the rear tie end being a direct continuation of the neckband portion and passing through the knot, the latter knot comprising a loop portion extending around the rear tie end so as to tend to laterally move the said front tie end at one edge thereof to disfigure the necktie, and an element 55 interconnecting the edge portions of the front tie end at the rear face thereof and in proximity to the knot to anchor said edge of the front tie end while permitting the latter to be downwardly pulled to tighten the knot, said element being substantially less in length than the width of the front tie end and producing a free fold in the 60 latter. 65

5. A four-in-hand necktie comprising a neckband portion, movable front and rear tie ends, and a knot, a tacking for the knot solely at the lower end of the knot to prevent opening thereof, and a thread substantially less in length than the width of the front tie end interconnecting the edges of the front tie end in proximity to the knot, said thread freely embracing the rear tie end, and a lateral obstruction on the rear tie end 70 75

to prevent the latter from being wholly pulled through the knot.

6. A four-in-hand necktie having a permanent preformed knot, a front tie end extending through the knot, an element connected to the side edges of the front tie end adjacent to the knot and serving to pull them toward each other, a rear tie end passing between the element and

the front tie end, and a neckband portion continuous with the rear tie end and movable therewith through the knot, the rear tie end having a lateral projection to prevent withdrawal through the knot of the rear tie end, the said element lying in the path of said obstruction. 5

ALFRED SCHARLIN.
